Primary Examiner—Susan J. Lucas*Assistant Examiner*—Jennifer Rivard*Attorney, Agent, or Firm*—Madson & Metcalf[57] **CLAIM**

The ornamental design for a power module, as shown and described.

DESCRIPTION

FIG. 1 is a perspective view of the first embodiment of the

power module having five pins according to the present invention showing details of the top side and the female socket located on the front side of the power module;

FIG. 2 is a perspective view of the power module of FIG. 1 showing details of the male plug located on the back side of the power module;

FIG. 3 is a right side view of the power module of FIG. 1;

FIG. 4 is a top view of the power module of FIG. 1;

FIG. 5 is a back side view of the power module of FIG. 1 showing the male plug;

FIG. 6 is front side view of the power module of FIG. 1 showing the female socket;

FIG. 7 is a perspective view of the second embodiment of the power module having three pins according to the present invention showing details of the top side and the female socket located on the front side of the power module;

FIG. 8 is a perspective view of the power module of FIG. 7 showing details of the male plug located on the back side of the power module;

FIG. 9 is a right side view of the power module of FIG. 7;

FIG. 10 is a top view of the power module of FIG. 7;

FIG. 11 is a back side view of the power module of FIG. 7 showing the male plug; and,

FIG. 12 is a front side view of the power module of FIG. 7 showing the female socket.
